PUMP

Edvin Ossian Parcival Thege, Stockholm, Sweden,
assignor to Aktiebolaget Atlas Diesel, Stockholm, Sweden, a corporation of Sweden

Application January 9, 1933, Serial No. 650,942
In Sweden July 11, 1932

13 Claims. (Cl. 103—41)

The present invention relates to pumps and has particular reference to fuel pumps for supplying liquid fuel to internal combustion engines.

In several forms of pumps as heretofore constructed, the quantity of fuel delivered by the pumps is controlled by adjustment of the position of the pump plunger or equivalent pumping element, but due to the unbalanced pressure on such member of the liquid being pumped the adjustment thereof is accomplished only by the application of sufficient force to overcome the existing unbalanced fluid pressure. In the case of fuel pumps for injection engines such pressure is so high that adjustment of this kind of pump is difficult if not impossible with, for example, a centrifugal speed governor of practical size.

It is a general object of the present invention to improve upon prior pump construction of this general kind. This is accomplished by providing a pump in which what may be termed the pumping member of the pump is divided to provide a part adjustable to determine the quantity of fuel delivered by the pump, which part is balanced or substantially balanced with respect to liquid pressure, and a second part which sustains the liquid pressure load incident to the pumping operation.

For a better understanding of the invention and the manner in which the above mentioned and other and more detailed objects of the invention are attained, reference may be had to the ensuing description of suitable forms of apparatus for carrying the invention into effect.

In the accompanying drawing forming a part of this specification—

Fig. 1 shows in longitudinal section and in more or less diagrammatic form a pump embodying the invention; and

Fig. 2 is a view in longitudinal section of another pump embodying the invention.

The driving shaft 1 of the pump, Fig. 1, is provided with a cam 2, which acts upon a roller 3 journaled in a hollow plunger or tappet part 4, which is slidably but not turnably mounted in the pump casing and is forced downwardly toward the cam by a spring 5. The part 4 is provided with inner screw-threads 6, which engage outer screw-threads 7 provided on a plunger 8, which is reciprocable in the pump casing. The part 4 is prevented from rotating by any suitable means for instance the usual groove and tongue device. A toothed wheel 9 is turnably but not slideably mounted in the pump casing and may be rotated manually or by a governor by means of any suitable motion transmitting de-

vice. Two arms 10 extend from the toothed wheel 9 downwardly and between lateral projections 11 on the plunger 8, so that the plunger is caused to rotate with the toothed wheel 9 as the latter is rotated, but may be moved axially relative to the same.

12 is the pump delivery chamber, in which the top end of the plunger 8 operates. With the said chamber a channel 13 communicates, provided with a fuel admission valve 14 and a delivery valve 15 for the fuel fed by the pump, for example, to the combustion chamber of the engine. 16 is an overflow valve, which is acted upon by a spring 17 and through a channel 18 returns to the fuel supplying channel 19 fuel, 15 superfluous for the working stroke of the engine piston. A pin 16^x extends from the said valve downwardly into the pump chamber 12 and may be acted upon by the plunger 8 in the manner stated below. A channel 20 extends through the 20 plunger 8 and connects the chamber 12 with a chamber 21 provided in the lower part of the plunger. Chamber 21 may be termed a balancing chamber situated between the parts 4 and 8 and in the embodiment illustrated this chamber is closed by an auxiliary member in the form of a plunger 22 slidably mounted in and closely fitting the wall of the chamber, and held by spring 23 against the bottom of the threaded recess in part 4.

The tappet part 4 and plunger part 8 may be said to constitute a divided or compound pumping member, the latter part being carried by and deriving motion through the former and being adjustable with respect thereto.

During the downward stroke of the pumping member of the fuel pump described above fuel is sucked into the chamber 12 through channel 19 and valve 14 and during the upward stroke of this member, fuel is forced through the valve 15 and into the combustion chamber of the engine. Owing to the fact that chamber 12 communicates with chamber 21, the pressure in chamber 12 is transmitted to chamber 21 and to the auxiliary member 22, which consequently will be subjected to this pressure during the working stroke of the pumping member while the plunger 8 is subjected to practically no unbalanced pressure. If the diameter of the member 22 is equal to the diameter of the top part of the plunger 8, the member 22 will transmit to part 4, which will in turn transmit to the cam 2, the whole pressure exerted by the fuel while it is being forced out from the pump chamber 12. Consequently, the plunger 8 is 55

wholly relieved of the pressure exerted by the fuel and for that reason it may easily be adjusted by the governor of the engine.

During its upward stroke the plunger 8 enters 5 into contact with the overflow valve pin 16^x at a moment adapted to the load of the engine and opens valve 16, so that fuel superfluous for the driving of the engine is discharged through the channel 18 to the fuel supplying channel 19. The 10 moment at which the valve 16 is opened is determined in such manner, that the plunger 8 is turned by means of the toothed wheel 9 to a higher or lower position in the part 4, and consequently brings the top end of plunger 8 to a 15 position nearer to or farther from the overflow valve 16, which results in that the valve is opened at an earlier or later moment respectively and that a smaller or greater quantity of fuel respectively is fed into the combustion chamber of the engine.

20 In the fuel pump shown in Fig. 2 the plunger part of the pumping member also serves as a controlling slide valve by discharging from the pump chamber at the end of its upward stroke, excess fuel which is unnecessary for the working stroke 25 of the engine piston. The pump is provided in a casing A. Plunger 24 is slideable in a lining 25 and is provided at its lower end with outer screw-threads 26, engaging inner screw-threads 27 of a plunger or tappet part 28. Part 28 is guided by 30 the lining 29 and is prevented from turning for instance by the known groove and tongue connection. Part 28 is forced downwardly by a spring 30. The driving shaft 31 of the pump is provided with a cam 32, which acts upon a suitably shaped roller 34, journaled in an arm 35, which is swingable on a pin or shaft 33 and transmits the driving power to the compound pumping member comprising parts 24 and 28. A worm wheel 36 is journaled on the lining 25 between 40 two abutments, preventing the same from moving axially. With the said worm wheel 36 meshes a screw spindle 37, which is journaled in the casing A and may be adjusted manually or by means of a governor. Two arms 38 extend 45 downwardly from the worm wheel 36 and between lateral projections on the plunger 24, so that the latter is turned by the worm wheel 36 when rotated but may be moved axially relative to the worm wheel 36. Owing to the screw-threaded 50 engagement of the part 24 with the plunger 28, the plunger 24 may be adjusted to different positions vertically by turning the screw spindle 37. The fuel supplying channel is designated by 40 and communicates through a passage 41 with the 55 space below the spring actuated suction valve 43 of the pump. The chamber 44^x above the valve 43 communicates through channels 44 with the pump chamber 45. The delivery valve 46 of the pump leads to a channel which may be connected 60 to the combustion chamber of an engine. A channel 47 is provided in the plunger 24 and leads from the pump chamber 45 to a chamber 48 provided in the lower end of the plunger 24. An auxiliary member in the form of a plunger 49 is 65 slideably mounted in the said chamber 48 and fits closely to its wall. Plunger 49 is forced against the bottom of the recess in part 28 by a spring 50. Lateral openings 51 extend from the channel 47 and in the outer surface of the plunger 24 a groove 52 is provided, preferably extending round the plunger. A groove 53 corresponding to the said groove 52 is provided in the inner side of the lining 25. Radial openings 54 and 55 are provided in the top part of the pump, leading from

the chamber in which the plunger 24 operates, and to the fuel supplying channel 40. The distance between the said openings 51 from the lower edge of the groove 53 is equal to the distance between the top edge of the groove 52 and the openings 54. 5

As the compound pumping member is moved downwardly by the spring 30, fuel is sucked from the supply channel 40 through passage 41, valve 43, channels 44 and into the pump chamber 45. 10 As the compound pumping member is then moved upwardly by the cam 32, fuel is forced from the chamber 45 through the channels 44, past the valve 43, now closed, and into the chamber 44^x and further through the valve 46 to the combustion chamber of the engine. As, during the upward motion of the plunger 24, the openings 51 arrive at the groove 53, the groove 52 at the same times arrives at the openings 54 and in this manner a passage for fuel superfluous for the working stroke of the engine piston and leading from the pump chamber 45 is effected viz 47, 51, 53, 52, 54 and 55. The moment at which the said passage is opened, is dependent on the position vertically into which the plunger 24 has been adjusted manually or by the governor. At a greater load of the engine the compound pumping member is shortened, which results in discharging superfluous fuel through the said passage at a later moment than when this member is elongated at a 20 smaller load of the engine. In the case last mentioned the plunger 24 operates at a higher position and consequently opens the passage for the superfluous fuel at an earlier moment. The plunger 24 may also be adjusted into such a position vertically that the passage 47, 51, 53, 52, 54 and 55 is opened or will be opened just at the starting of the upward stroke of the plunger 24, in which case no fuel is fed into the combustion chamber of the engine and the engine will stop. 30

In the form of apparatus shown in Fig. 2, as well as in the form shown in Fig. 1, the auxiliary member is exposed to the pressure of the fuel in the pump chamber during the working stroke of the pumping member and transmits this pressure to the tappet part, which in turn transmits the pressure to the actuating cam. The plunger part 24 is, because of this arrangement, not exposed to unbalanced liquid pressure and acts entirely 45 as a control member. The governor mentioned above may be of any known or suitable construction and connected to the screw spindle 37 by a motion transmitting device of any of the conventional types. 50

Through the provision of the grooves 52 and 53 a double surface closure between the plunger 24 and the lining 25 is effected, which renders the escaping of fuel necessary for the working stroke of the engine piston difficult or prevents the same. 60 This is of great importance, because the fuel, while being injected into the combustion chamber of the engine, is subjected to a very great pressure. The surface closure may be still more increased through the provision of one or more additional pairs of grooves of the shown type. 65

While in compliance with the patent statutes I have described and illustrated preferred embodiments of the invention by way of example, it will be apparent to those skilled in the art that the 70 principles of the invention may be embodied in apparatus of different construction than that herein disclosed, and the invention is accordingly to be understood as embracing all such changes and modifications in the apparatus as may fall 75

within the scope of the appended claims when construed as broadly as the state of the prior art warrants.

I claim:

- 5 1. In a fuel pump intended especially for feeding fuel into an internal combustion engine, the combination of a delivery chamber, a divided member, a mechanism reciprocating said member, said member comprising a part acted upon by
 10 said mechanism and a part adjustable with relation to the first mentioned part for controlling the quantity of delivered fuel, one end of the adjustable part communicating with the delivery chamber, a counter bore in said adjustable part
 15 having a shoulder facing away from the delivery chamber, said counter bore communicating with said delivery chamber, and an auxiliary member slidably mounted in the counter bore, subject to the fluid pressure therein and resting on the
 20 first mentioned part of the divided member.

2. A pump as claimed in claim 1 characterized by the cross sectional area of the pressure sustaining auxiliary member being substantially equal to the cross sectional area of said one end
 25 of the adjustable part.

3. In a fuel pump intended especially for feeding fuel into internal combustion engines, the combination of a delivery chamber, a divided piston, a mechanism reciprocating said piston, said piston comprising a part acted upon by said mechanism and a part adjustable with relation to the first mentioned part for controlling the quantity of delivered fuel, one end of the adjustable part communicating with the delivery chamber, a counter bore in said adjustable part having a shoulder facing away from the delivery chamber, said counter bore communicating with said delivery chamber, an auxiliary member slidably mounted in the counter bore, subject to the fluid pressure therein and resting on the first mentioned part of the divided piston, and means for adjusting said adjustable part.

4. A pump as claimed in claim 3 characterized in that the adjustable part is arranged like a slide valve for controlling the supply of fuel to the engine.

5. A pump as claimed in claim 3, characterized in that said piston is provided with a passage communicating with the delivery chamber, a discharge passage in the casing for fuel superfluous for the working stroke of the engine piston, recesses provided in the surface of the adjustable part between said passages and in the wall of the casing and cooperating with the recesses of the adjustable part, said recesses and said passages together constituting a flow line for the superfluous fuel when said member is in open position.

6. In reciprocating pump apparatus, pump actuating mechanism, means providing a pump delivery chamber, a multiple-part pumping member having a first part reciprocated by said mechanism, a plunger part carried by said first part and working in said delivery chamber, and means to adjust said plunger part relative to said first part to determine the quantity of fluid delivered by the pump, said plunger part being subjected at its opposite ends to substantially equal total fluid pressures.

7. In reciprocating pump apparatus, pump actuating mechanism, means providing a pump delivery chamber and a multiple-part pumping member having a first part reciprocated by said mechanism and a second part carried by and de-

riving motion from said first part and adjustable with respect to said first part to determine the quantity of fluid delivered by the pump, said pumping member providing a second chamber in communication with the pump delivery chamber and said second part having opposed end surfaces exposed respectively to the pressure of fluid in said delivery chamber and in said second chamber.

8. In reciprocating pump apparatus, pump actuating mechanism, means providing a pump delivery chamber, a multiple-part pumping member having a first part reciprocated by said mechanism and a second part carried by and deriving motion from said first part and adjustable with respect to said first part to determine the quantity of fluid delivered by the pump, said second part having one end working in said delivery chamber, one of said parts being recessed to provide a second chamber, the opposite end of said second part being exposed to pressure in said second chamber, and a connection providing communication between said second chamber and said delivery chamber.

9. In reciprocating pump apparatus, pump actuating mechanism, means providing a pump delivery chamber, a multiple-part pumping member having a first part reciprocated by said mechanism and a second part carried by and deriving motion from said first part and adjustable with respect to said first part to determine the quantity of fluid delivered by the pump, said second part having one end working in said delivery chamber and having a recess in the end of the part opposite said delivery chamber, means moving with said first part and slidably mounted in said recess and closing the end of the recess opposite the delivery chamber whereby to provide a second chamber and a connection placing said second chamber in communication with said delivery chamber.

10. In reciprocating pump apparatus, pump actuating mechanism, means providing a pump delivery chamber and a multiple-part pump member having a first part reciprocated by said mechanism and a second part carried by and deriving motion from said first part and adjustable with respect to said first part to determine the quantity of fluid delivered by the pump, said second part having a first end working in said delivery chamber and having a recess in the end of the part opposite said first end, means moving with said first part and slidably mounted in said recess and closing the end of the recess opposite the delivery chamber whereby to provide a second chamber, the last mentioned means having an area exposed to fluid pressure substantially equal to the area of said first end of said second part, and a connection placing said second chamber in communication with said delivery chamber.

11. In reciprocating pump apparatus, pump actuating mechanism, means providing a delivery chamber, a compound pump member comprising a tappet part reciprocated by said actuating mechanism and having a recess therein and a pump plunger part having one of its ends threaded in said recess to provide for adjustment of the pump plunger part with respect to the tappet part to determine the quantity of fluid delivered by the pump, said plunger part having a first end working in said delivery chamber, the end of said plunger part opposite said first end being recessed to provide a second chamber, a connection placing said second chamber in communication with the delivery chamber, and means for

- turning one of said parts relative to the other of said parts to effect adjustment of said pump plunger part to change the quantity of fluid delivered by the pump.
- 5 12. In reciprocating pump apparatus, pump actuating mechanism, means providing a delivery chamber, a compound pump member comprising a rotationally fixed tappet part adapted to be reciprocated by said mechanism and a rotatably mounted plunger part threaded in said tappet part, said plunger part having a first end working in said delivery chamber and means for turning said plunger part to adjust it with respect to the tappet part to determine the quantity of fluid 10 delivered by the pump, the end of said plunger part opposite said first end being recessed to provide a second chamber, and a connection placing said second chamber in communication with said delivery chamber.
- 5 13. In reciprocating pump apparatus, pump actuating mechanism, means providing a pump delivery chamber, a compound pumping member comprising a tappet part adapted to be reciprocated by said mechanism and a rotatably mounted plunger part threaded in said tappet part, said plunger part having a first end working in said delivery chamber, means for turning said plunger part to adjust it with respect to the tappet part to determine the quantity of fluid delivered by the 10 pump, the end of said plunger part opposite said first end being recessed to provide a second chamber, means slidably mounted in said recess and adapted to move with said tappet part for closing said chamber, and a connection passing through said plunger part for placing said second chamber in communication with said delivery chamber. 15
